Attorney.

UNITED STATES PATENT OFFICE.

CARMINE J. SALVIOLO, OF BROOKLYN, NEW YORK.

DISPENSING-CAN.

1,330,351.

Specification of Letters Patent. Patented Feb. 10, 1920.

Application filed June 11, 1919. Serial No. 33,383.

To all whom it may concern:

Be it known that I, CARMINE J. SALVIOLO, a citizen of the United States, and residing at Brooklyn, Kings county, New York, have invented certain new and useful Improvements in Dispensing-Cans, of which the following is a specification.

This invention relates to dispensing cans and more especially to receptacles to contain powder, granulated material or pills and its object is to provide a vertically moving cup to be located in the nozzle of a box or can and adapted to be filled with powder when the box is inverted. To discharge the load of powder a lever pivoted in a slot in the nozzle is operated from the outside and is connected with and moves the cup toward an opening which is normally closed but whose cover is a branch of the lever. When the outer end of the lever is therefore depressed it opens the cover and causes the cup to discharge the desired amount of the contents of the box. The cover prevents deterioration of the material and it can be displaced when the box is reversed.

These and other objects and details of the invention are more fully described in the following specification, set forth in the appended claims and illustrated in the accompanying drawings, wherein:

Figure 1 is a side elevation of a box for powder to which the invention is applied.

Fig. 2 is a vertical sectional view of the same.

Fig. 3 is a similar view inverted and with the cover open.

Fig. 4 is a perspective view of the cup removed.

Fig. 5 is a detail of a modification.

The attachment is of three pieces and without any actual connections. The lever playing in the slot 5 of the nozzle 6 and consisting of a flattened thumb piece 7, the circular cover 8 and an arm 9 within the nozzle, the latter having the notch 10 and carrying the hanger 11 of the cup 12.

The arm 9 fits through and plays in a slot 13 of the hanger and the notch limits the downward movement of the cup and it will be seen in Fig. 2 that the cover 8 limits the downward movement of the lever and its parts while the outer movement is limited by the legs 14 of the cup.

When the box or can is reversed a certain quantity of the powder therein is taken

into the cup through the spaces between the legs 14 and when the thumb piece is pressed inward, the arm and cover are also thrown down, the arm carrying the cup 12 which forces a certain amount of its contents outward through the hole 15.

The cup 12 is normally held down by a spring 16 struck from a steel bar 17 lodged in the base of the cap 18 and passing into a slot in the lip 19 that depends from the cup.

The whole mechanism is very simple and cheap with no pins or pivots and the parts are few and not liable to get out of order; the lever being fulcrumed in the side of the nozzle and the bend of the arm making it difficult to remove it.

It is evident that its use need not be confined to solids nor powders but that in certain instances it may be constructed and arranged to dispense liquids in small quantities.

The parts may also be modified without departing from the essential features above described or from the scope of the appended claims.

With the aid of the spring, the legs of the cup, the hanger, the arm and the opening any granulated or pulverized material which might lump or be disposed to clog the dispenser will be loosened or broken up before leaving the nozzle. The length of the legs may be regulated to determine the amount of material to be dispensed and the cup may be reduced to a mere skeleton so that the action of the spring is for the closing of the cover alone.

In order that the operating lever may not be actuated accidentally while being shipped or when in a traveling bag, or on being dropped it may be provided with a keeper 19 pivoted beneath the thumb piece 7 and adapted to come in contact with the cap 18 so that the thumb piece cannot be depressed, but the latter may be released by throwing the keeper out into the position shown in dotted lines and the lever may then be operated.

What I claim as new is:

1. In a dispensing can, the combination of a nozzle having an opening, a cover for the opening, a cup normally below the nozzle, and means for simultaneously raising the cover and advancing the cup.

2. In a dispensing can, the combination of a nozzle having an opening, a cover for

105

110

the opening, a cup suspended below the nozzle, and a lever adapted to open the cover and advance the cup.

3. In a dispensing can, the combination of a nozzle having an opening, a cup with flexible legs adapted to play into the nozzle, a cover for the opening, and a lever carrying the cover and adapted to advance the cup.

4. In a dispensing can, the combination of a nozzle having an opening, a lever comprising a cap for the opening, a thumb piece on the lever, an arm at one end of the lever,

a cup below the nozzle and having guide legs to play therein, means connecting the arm with the cup, and a spring to return the cup to its normal position. 15

In testimony whereof I have signed my name to this specification in the presence of two subscribing witnesses, this 22 day of May, 1919.

CARMINE J. SALVIOLO.
